UNITED STATES PATENT OFFICE.

BEN B. DE MASTERS, OF KANSAS CITY, MISSOURI.

HAT IDENTIFYING ATTACHMENT OR MARKER.

1,315,473.

Specification of Letters Patent.

Patented Sept. 9, 1919.

Application filed February 5, 1918. Serial No. 216,123.

To all whom it may concern:

Be it known that I, BEN B. DE MASTERS, a citizen of the United States, residing at Kansas City, in the county of Jackson and

5 State of Missouri, have invented certain new and useful Improvements in Hat Identifying Attachments or Markers, of which the following is a specification.

This invention relates to hat identifying 10 attachments and more especially to means for guarding against loss of a hat through the unintentional carrying off of the same by another person than the owner.

The object of the invention is to produce a 15 device for securement within a hat and adapted for adjustment from a normal position which it occupies when the hat is in service on the head, to an abnormal position which it should occupy when the hat is 20 placed on a hook, shelf or the like, in a restaurant or other place where a number of people are assembled, the device when in the abnormal position affording an obstruction to the proper and comfortable fitting of the 25 hat upon the head.

A further object is to produce a device of the character set forth, which can be manufactured in large quantities at low cost, and which requires no skill for securement to a 30 hat and is adapted for holding a name and address tag or the like.

With these objects in view the invention consists in certain novel and useful features of construction and combinations of parts as 35 hereinafter described and claimed; and in order that the invention may be fully understood reference is to be had to the accompanying drawing, in which:—

Figure 1, is a fragmentary vertical sectional view of a hat equipped with an identification device embodying one form of my 40 invention.

Fig. 2, is an inner face view of the attachment as applied to a hat and adjusted to 45 "abnormal" position.

Referring to the drawing in detail, 1 is a U-shaped member for attachment to the sweatband or the like of a hat, and 2 is a flat metal member for pivotal connection with 50 member 1, which, if of the type set forth, will be secured in position by extending its arms through the sweatband 3 of the hat 4, and clenching them in such position so that the member shall be held firmly in a fixed 55 position.

In the embodiment of the invention shown,

the flat metal member 2, is provided with one or more tongues 5, bent to form hinge-members or coils around the body-portion of the member 1, the hinge-point occurring at the 60 upper edge of the sweatband for a purpose which is hereinafter explained.

At one end member 2, is bent to form a lateral projection 6, or said projection may be otherwise produced, its object being to 65 offer an obstruction, when below the upper edge of the sweatband, to the hat being placed upon the head without the wearer becoming instantly aware that something unusual is interposed between his head and 70 hat.

In the preferred construction of the device, the member 2 will be pivoted at an intermediate point to the member 1, so that when the said projection is in its depressed 75 or abnormal position, a part of the member shall project beyond the upper edge of the sweatband, and when said projection is in elevated position, as when the hat is upon the head, said part will lie between the 80 sweatband and the body of the hat and hence, utilize the head of the wearer through pressure on the said band, in holding the member 2 in normal position, that is with the said projection above the plane of the 85 sweatband a sufficient distance to avoid contact with the head.

The end of member 2, not only constitutes means for retaining the device in normal position, but also may be utilized as a 90 holder for a name and address slip or tag. As shown the side margins are bent back to form grooved flanges 7 for overlapping the side edges of a slip or tag 8 containing the name, address and telephone number 95 or the like, of the owner of the hat. To prevent endwise movement of the tag after it is placed in position, the tongue 9 at the extremity of the member is bent down upon the tag, movement of the latter being 100 further guarded against by providing the member with the protuberance 10.

In Fig. 1, the dotted lines show the device in normal position, in which position it will be noted, the lateral projection occupies such 105 position that it will not interfere with the proper fitting of the hat upon the head, and can not fall over against the head because of the pressure of the latter against the opposite end of the pivoted member, said pressure being applied through the sweatband. When the hat is removed and placed 110

on a hook or the like, in a public place, the owner, before he disposes of the hat will adjust the device from "normal" to "abnormal" position so that neither he nor any other person can place the hat upon his head without the wearer becomes aware instantly that the hat fits improperly. Upon removing the hat the cause of the trouble will become apparent, and the person in charge of the hat will have the name and address tag under observation.

From the above description it will be apparent that I have produced a device for identifying hats and incidentally protecting them against unintentional removal, which embodies the features set forth as desirable in the statement of the object of the invention, and while I have illustrated and described the preferred form of construction, it will be understood that it may be changed in many respects without departing from the spirit and scope of the appended claims.

I claim:

1. A hat identifying device or marker comprising an inverted U-shaped member having its arms extended through and firmly clenched to the sweat band of the hat, a flat member provided intermediate its length with hinge coils engaging the body or horizontal portion of the U member and formed at one end with a projection; said member being adapted to stand upright with the end having the projection, fitted against the inner side of the sweat band and the

other end projecting upward into the body of the hat above the sweat band, or with the last-named end interposed wholly between the sweat band and the immediately surrounding part of the hat and the end provided with the projection, projecting upward into the body of the hat above the sweat band.

2. A hat identifying device or marker comprising an inverted U-shaped member having its arms extended through and firmly clenched to the sweat band of the hat, a flat member provided intermediate its length with hinge coils engaging the body or horizontal portion of the U member and formed at one end with a projection; said member being adapted to stand upright with the end having the projection, fitted against the inner side of the sweat band and the other end projecting upward into the body of the hat above the sweat band, or with the last-named end interposed wholly between the sweat band and the immediately surrounding part of the hat and the end provided with the projection, projecting upward into the body of the hat above the sweat band; the end without the projection being formed at the same side of the plate as said projection, with parallel grooved side flanges, a protuberance adjacent the hinge point, and a tongue at the upper end for conjointly securing a tag firmly in place.

In testimony whereof I affix my signature.
BEN B. DE MASTERS.
